UNITED STATES PATENT OFFICE

EDWIN H. STEEDMAN, OF ST. LOUIS, MISSOURI

COOLING UNIT FOR REFRIGERATING SYSTEMS

Application filed February 6, 1928. Serial No. 252,299.

This invention relates to cooling units for refrigerating systems of small capacity, such as are used in domestic refrigerators, ice cream cabinets and similar apparatus.

The main object of my invention is to provide an efficient cooling unit of inexpensive construction and attractive appearance, which is equipped with a "cold" plate that forms a very efficient heat absorption means for rapidly abstracting heat from a substantially flat bottom container that holds an ice cream mixture or other substance which it is desired to cool, chill or freeze.

Figure 1 of the drawings is a front elevational view, partly in vertical section, of a cooling unit constructed in accordance with my invention.

Figure 2 is a top plan view, partly broken away, of the cooling unit shown in Figure 1.

Figure 3 is a vertical longitudinal sectional view of the cooling unit shown in Figure 1; and

Figure 4 is a transverse sectional view, illustrating another form of my invention, wherein the "cold" plate of the unit is formed from an element separate and distinct from the hollow side walls of the unit and attached to said walls.

Referring to Figures 1, 2 and 3, which illustrate one form of my invention, A and B designate two shells or members arranged one within the other and provided with cooperating portions that are adapted to be combined in such a way as to form a double wall shell that contains a refrigerating medium and which surrounds a space at the center of the cooling unit that is adapted to receive material or articles which it is desired to cool, chill or freeze, said members A and B being preferably formed from sheet metal. The inner member A is provided with two vertically-disposed side walls 1, a top wall 2 integrally connected to said side walls, and a flat or substantially flat bottom wall 3 integrally connected to said side walls. The outer member B is of similar form and is provided with side walls 1*, a top wall 2* and a bottom wall 3*.

all integrally connected together. The marginal edges of the side wall portions and of the bottom wall portions of said members A and B are connected together by gas-tight joints 4 preferably produced by a brazing, 55 welding, soldering or similar seaming operation. The opposed top wall portions 2 and 2* of the members A and B are preferably so shaped that they will form the bottom and top wall, respectively, of an integral 60 float chamber 5 for the float 6 that controls the valve which governs the admission of the refrigerating medium to the passageway formed by the opposed portions of the members A and B. It is immaterial how the 65 top and bottom walls of the float chamber are joined together. In the embodiment of my invention herein shown, the float chamber 5 is provided with a front wall 7 formed preferably by a plate, casting or other element that is connected by gas-tight joints with the front edges of the top wall portions of the members A and B. Said float chamber 70 can be provided with a rear wall of similar construction, or the top and bottom 75 walls of said chamber can be bent inwardly towards each other, as shown in Figure 3, and joined together by a gas-tight joint 8 produced by a welding, brazing or other suitable seaming operation. In order to reinforce and strengthen the opposed portions of the members A and B so as to prevent distortion, due to internal pressure, some of the opposed portions of said members can be connected together at numerous points 9 80 within their marginal edges by spot welding, or in any other suitable way, and if it is desired to increase the surface of the unit that is exposed to the air in the refrigerator or other structure in which the 85 unit is used, fins 10 can be attached to the exterior of the unit, as indicated in broken lines in Figure 2. Owing to the fact that the refrigerating medium is in efficient thermal conductivity with the bottom wall 3 of the 90 space α of the unit, this portion of the unit constitutes a "cold" plate that forms a very efficient heat absorption means for rapidly abstracting heat from an ice cream mixture or other substance in a container that is

arranged in an upright position on the bottom wall 3. The portion 3 of the cold plate that serves as a supporting surface for the container that holds the material to be chilled or frozen is preferably flat, so that when a substantially flat bottom container is set in an upright position on the cold plate a very efficient transfer of heat from the substance in the container to the refrigerating medium will be obtained, due to the fact that the bottom of the container is maintained in good and adequate thermal conductivity with the heat absorption means, and if relatively rapid freezing or cooling is desired, water can be spread over the bottom of the container or over the portion of the cold plate on which the container rests, so as to fill any voids or interstices between said opposed surfaces, and thus insure a good thermal connection between the container and the heat absorption means. In order to facilitate the use of water or other suitable material used to insure good and adequate thermal conductivity between the container that holds the material being frozen or cooled and the heat absorption means on which said container is positioned, the bottom portion 3 of the member A that constitutes the top surface of said heat absorption means is preferably provided adjacent its marginal edge with a rib 11, as shown in Figure 3, so as to form a pocket or depression on the cold plate of the unit that is capable of holding a thin film of liquid. The inner faces of the side walls of the space α of the unit are preferably provided with horizontally-disposed supports 12 that are used to sustain pans or trays (not shown) which hold water or other material that it is desired to freeze, chill or cool, said supports 12 being combined with said side walls in any suitable way.

If desired the unit can consist of an open bottom structure equipped with a cold plate 45 formed by a separate member of any desired form, as, for example, a hollow member 3^b of the kind illustrated in Figure 4, which is connected by welding, brazing or any other suitable method to the hollow side walls of 50 the unit, said member 3^b being provided with ports or openings 3^c that establish communication between the interior of same and the interior of the hollow side walls of the unit, so as to permit the refrigerating medium to circulate freely through said cold plate.

The float chamber 5 is provided with a hole of sufficient size to permit the float 6 to be introduced into said chamber, and said hole is normally closed by a cover plate or closure 16 equipped with a gasket 17 and held in position by fastening devices 18. Said hole can be located in any suitable portion of the float chamber, but it is herein shown as being formed in a plate 7 that constitutes the front wall of the float chamber.

The valve mechanism that governs the admission of the refrigerating medium to the unit is preferably combined with or carried by the closure 16 and is herein illustrated as comprising a valve 19 which is combined 70 with the float 6 in such a way that when the level of the refrigerating medium in the float chamber 5 drops, the float 6 will move in a direction to open the valve 19, and thus admit more refrigerating medium to the 75 float chamber. Thereafter, when the level of the refrigerating medium in the float chamber rises, the float 6 will move in a direction to close the valve 19. The gas from the evaporated refrigerating medium is 80 sucked off by the compressor (not shown) through a conduit that communicates with a hole 20 in the closure 16. The valve structure also preferably comprises a shut-off valve (not shown) that can be used for cutting off the supply of the refrigerating medium to the controlling valve 19, said cut-off valve being accessible by removing the gas-tight plug 22, shown in Figure 1.

A refrigerating unit of the construction above described is inexpensive to manufacture, as it is constructed from shaped members, preferably sheet metal members, which, after being assembled, are connected together by a simple seaming operation, so as 90 to produce a gas-tight, double wall shell that surrounds a center space for receiving articles or materials which it is desired to cool, freeze or chill; it is not apt to leak when in use and is more efficient than the 95 conventional tubular cooling unit, due to the fact that it has relatively few joints and is provided with large unobstructed passageways through which the refrigerating medium can circulate freely. The unit is of 100 good mechanical appearance and it can be provided with an attractive finish, on account of the fact that it is constructed from material that has a smooth surface. Moreover, it is compact; it is exceptionally efficient, on account of the relatively great area 1 of its double walls, and it can be used successfully for freezing an ice cream mixture or similar mixture, due to the fact that the lower portion of the unit is constructed so as 11 to form a flat or substantially flat "cold" plate that will abstract heat rapidly from material confined in a substantially flat bottom container positioned on said cold plate.

Having thus described my invention, what I claim as new and desire to secure by Letters Patent is:

1. A cooling unit for refrigerating systems, composed of two shells arranged one within the other in spaced relation and provided with co-acting portions which form hollow side walls that contain a refrigerating medium and which surround a center space in which articles or materials may be placed, the hollow wall at the top of said 1

space serving as a float chamber, the hollow wall at the bottom of said space serving as a cold plate for abstracting heat rapidly from a flat bottom receptacle positioned in said 5 space, and the hollow walls at the sides of said space serving as circulating passageways which connect the cold plate with the float chamber.

2. A cooling unit for refrigerating systems, composed of an outer shell having a top, a bottom and side walls joined together, an inner shell provided with corresponding walls arranged inside of the outer shell in spaced relation with same so as to form a 10 space for receiving materials or articles, and a refrigerating medium in the space between said shells, the top walls of said shells being spaced far enough apart to form a float chamber and the rear end portions of said 15 top walls being bent towards each other and connected together by a gas-tight joint, the co-acting side wall and bottom wall portions of said shells consisting of flat plate-like members connected together at intervals by 20 25 spot welds.
